US00D784512S

(12) **United States Design Patent** (10) **Patent No.:** **US D784,512 S**
(45) **Date of Patent:** **** Apr. 18, 2017**

(54) **VENTILATOR GRILL**

(71) Applicant: **Broan-NuTone LLC**, Hartford, WI (US)

(72) Inventors: **Kenneth J. Jonas**, Mequon, WI (US); **Corey Scott Jacak**, West Bend, WI (US); **Benjamin Thorpe Puffer**, Hartford, WI (US); **Michael J. Alevin**, West Bent, WI (US)

(73) Assignee: **Broan-NuTone LLC**, Hartford, WI (US)

(**) Term: **14 Years**

(21) Appl. No.: **29/514,063**

(22) Filed: **Jan. 8, 2015**

(51) **LOC (10) Cl. 23-04**

(52) **U.S. Cl.**

USPC **D23/388; D23/412**

(57) **CLAIM**

The ornamental design for a ventilator grill, as shown and described.

DESCRIPTION

FIG. 1 is a perspective view of the first embodiment of the ventilator grill.

FIG. 2 is a front view thereof. The back view being a mirror image of this view.

FIG. 3 is a side view thereof. The other side being a mirror image of this side view.

FIG. 4 is a top view thereof.

FIG. 5 is a bottom view thereof.

FIG. 6 is a perspective view of the second embodiment thereof.

FIG. 7 is a front view thereof. The back view being a mirror image of this view.

FIG. 8 is a side view thereof. The other side being a mirror image of this side view.

FIG. 9 is a top view thereof.

FIG. 10 is a bottom view thereof; and,

FIG. 11 is a cross-section view of the first embodiment taken along lines 11-11 of FIG. 4.

The features shown in broken lines depict environmental subject matter only and form no part of the claimed design.

1 Claim, 11 Drawing Sheets
